UNITED STATES PATENT OFFICE.

CARL WILHELM VOLLMANN, OF MONTREAL, QUEBEC, CANADA.

CONDENSER AND COOLER.

1,033,132.

Specification of Letters Patent. Patented July 23, 1912.

Application filed March 31, 1906. Serial No. 309,177.

To all whom it may concern:

Be it known that I, CARL WILHELM VOLLMANN, of the city of Montreal, Province of Quebec, Canada, have invented certain new and useful Improvements in Condensers and Coolers; and I do hereby declare that the following is a full, clear, and exact description of the same.

My invention relates particularly to double pipe ammonia condensers and coolers, and it has for its object to provide a construction which will insure the cooling of the fluid being treated to approximately the same temperature as the cooling medium and cause the heat to be absorbed therefrom to a progressively increasing extent from the time it enters the apparatus until it is discharged therefrom, and at the same time obviate any chance of the circulation being retarded by liquefaction of the gaseous fluids in the early stages of their passage through the apparatus.

The invention may be said briefly to consist of a condenser constructed to alternately divide a body of the fluid being treated into a series of streams flowing through as many pipes, and unite and intermingle such streams, such fluid being caused for the purpose, to flow alternately through chambers which are independent of one another and a plurality of series of pipes effecting intercommunication between such chambers. For full comprehension, however, of my invention reference must be had to the accompanying drawings forming a part of this specification and in which similar reference characters indicate the same parts and wherein—

Figure 1 is a side elevation partly in longitudinal sectional view, of a condenser or cooler constructed according to my invention; Fig. 2 is an end elevation partly in transverse vertical sectional view, and Figs. 3 and 4 are enlarged sectional views taken at right angles to each other and illustrating the connection between the pipes and chambers and the former and its return bends.

The fluid to be condensed or cooled is conducted through pipes *b*, and the condensing or cooling medium through pipes *c* extending longitudinally through and beyond the ends of pipes *b* and being coupled together at their opposite ends by auxiliary coupling heads *d*. These parts are preferably constructed and arranged as usual, my invention having reference particularly

to the means for coupling the pipes *b* together.

My improved coupling means consists of a columnar series of hollow heads presenting chambers completely separated from one another, such heads being flanged as at *h* at their abutting ends and bolted together. The heads or chambers of each columnar series being completely separated from one another by webs *w* extending across and closing their abutting ends. A pair of these coupling columns are utilized with and constitute component parts of each double pipe coil, which they support independently of other steadyng devices. The top head *g* of one of the columns is formed with a flanged opening *i* to enable the ammonia-gas feed pipe to be coupled thereto and the bottom head *g'* has a flange *j* constituting a foot upon which the column stands, and the top coupling head of the other column is closed at its upper and lower ends and the bottom head *g'* thereof is also closed at its upper and lower ends and formed with an extension *k* flanged as at *k'* to constitute a foot, and it is also formed with a pipe connection *k*² to which is coupled the liquid ammonia conducting pipe. This top head *g* is constructed with three openings in one side to which are coupled three of the ammonia pipes *b* the opposite side having three openings of smaller diameter to receive a like number of water pipes *c* and the bottom head *g'* is similarly constructed, while the other heads *g*² of each columnar series are formed with six openings in each side, the openings in one side being of smaller diameter than those in the other side, while the number of pipes utilized depends of course upon the number of streams into which it is desired to divide the ammonia vapors entering the coil, and in some coils it is required to divide the same into more or less than three streams, but I have found a division into three preferable. Whatever number of divisions may be made care must be taken to secure a collective area of the pipes at least equal to the area of the passage through the head from which they receive their supply. By securing this minimum capacity of the pipes the ammonia is caused to travel at a uniform speed throughout the entire apparatus and unnecessary friction is avoided.

The means for coupling the pipes *b* to my improved coupling heads preferably con-

sist of a series of stuffing boxes *m* cast with flanges *m'* and the adjacent portions of the heads are cast with counterborings *g*³ and pairs of lugs *g*⁴ between which, and through 5 perforations in the flanged stuffing boxes; a series of bolts *n* are placed and they afford means whereby such stuffing boxes and the pipes *b* can be clamped tightly to the heads.

The means I prefer to use to couple the 10 pipes for conducting the water, or other condensing or cooling medium, together and secure them rigidly to the columns, consists of a series of auxiliary heads *d* (before mentioned) and *o*. The auxiliary heads *o* and *d* are of substantially circular cross-section, and in the form of return-bends and have 15 cleaning holes *d'*, closed by screw plugs *d*², in line with the pipes *c*. These auxiliary heads are constructed with nipple formations *r* adapted to constitute bushings and fit into counter borings *s* in the outsides of the main coupling heads *g* opposite to that containing the counterborings *g*³, while the opposite sides of such auxiliary heads are 20 cast with flanges *t*, and the contiguous portions of the main coupling heads with pairs of lugs *u* between which and through perforations in the flanges *t* a series of bolts *v* are inserted and afford means whereby 25 such auxiliary heads and the opposite ends of pipes *c* are coupled together in alternating pairs and secured rigidly to the main coupling heads *g*.

The pipes whereby the fluid to be 30 condensed or cooled is supplied and discharged, are indicated at 12, and 13 respectively and the condensing or cooling medium supplied and discharge pipes at 14, and 15 respectively.

40 The heads are retained in their proper positions relatively to one another and against displacement by the pressure in the heads by a series of retaining rings or collars *y* screwed upon the ends of the pipe 45 *c* and into tight contact with the heads, thereby allowing free expansion and contraction of the pipes *b*.

Operation: The operation of my improved apparatus for condensing and cooling ammonia gas is as follows, cold water being 50 used as a condensing medium. The condensing medium enters at 14 and flows alternately back and forth through the pipes *c* to the outlet 15. The ammonia vapor enters 55 through pipe 12 in a single stream and floods the uppermost chamber (constituted by the head *g*) of what may be termed the intake column, and simultaneously enters the spaces between the pipes *b* and *c* which lead 60 from such head, thus becoming divided into three independent film-like streams and in this manner it is delivered into the upper portion of the corresponding head at the opposite end of the coil. Upon entering 65 this last mentioned head the independent

streams unite and a thorough molecular subdivision results, the liquid molecules fall to the bottom and the gaseous molecules rise to the top owing to their specific gravity. Simultaneously with the flooding of this 70 head the fluid enters the next series of three independent spaces between the pipes *b* and *c* thus again separating such fluid into three independent streams. This process of alternate separating and uniting of the substance and (simultaneously with the uniting of the separated parts) the molecular division and subdivision, continues until the ammonia is finally delivered into the chamber constituted by the lowermost head *g'* 75 of the outlet column, from which it is discharged through pipe 13 thoroughly liquefied. During its course through the pipe *c*, the condensing medium absorbs the heat of the film like streams of ammonia vapor 80 thereby liquefying the same. The automatic molecular separation in the different chambers causes the gaseous fluid to flow through the uppermost pipe of the series and the liquid to flow through the lower- 85 most pipe of such series which insures a constantly free gas passage through the apparatus and effectively prevents the choking thereof by the liquefaction of a portion of the fluid in the early stages of the operation, while, as is a most important advantage, all the ammonia, whether before, during, or after liquefaction is subjected to the 90 condensing action of the water circuit, from the moment it enters the apparatus until it 95 is discharged, and during the intervals between each uniting and separating of the ammonia it is in its entirety (though divided), subjected to the heat absorbing action of the water thereby causing it to 100 emerge from the apparatus thoroughly liquefied and at practically the same temperature as the water when the latter is discharged.

What I claim is as follows:—

1. A condensing or cooling apparatus comprising a columnar series of hollow heads presenting chambers completely separated from one another and having recesses at the outside thereof, a second columnar series of hollow heads presenting chambers completely separated from one another and having recesses at the outside thereof, a plurality of pipes extending between the chambers of the two columnar series and bringing them into alternate communication by a zig-zag path from the top of one series which is provided with an inlet, to the bottom of the other series which is provided with an outlet, a plurality of tubes, each extending from the outside of one column through one of the said pipes and one of the recesses to the outside of the other column into one of the said recesses in the latter, collars screw-threaded on the ends of the said tubes, lo- 110 115 120 125 130

cated within the recesses and bearing against the hollow heads, and headers extending into such recesses and coupling the tubes in alternating pairs to form a continuous zig-zag coil having an inlet adjacent to the inlet to the columnar series and an outlet adjacent to the outlet of such columnar series.

2. A condensing or cooling apparatus comprising a columnar series of hollow heads presenting chambers completely separated from one another and having recesses at the outside thereof, a second columnar series of hollow heads presenting chambers completely separated from one another and having recesses, at the outside thereof, pairs of spaced lugs on the hollow heads, a plurality of pipes extending between the chambers of the two columnar series and bringing them into alternate communication by a zig-zag path from the top of one series which is provided with an inlet, to the bottom of the other series which is provided with an outlet, a plurality of tubes, each extending from

the outside of one column through one of the said pipes and one of the recesses to the outside of the other column into one of the said recesses in the latter, collars screw-threaded on the ends of the said tubes, located within the recesses and bearing against the hollow heads, headers extending into such recesses and coupling the tubes in alternating pairs to form a continuous zig-zag coil having an inlet adjacent to the inlet to the columnar series and an outlet adjacent to the outlet of such columnar series, perforated lugs on the headers and located opposite to the said spaced lugs and bolts held between the spaced lugs and passed through the perforated lugs to secure the headers in place.

In testimony whereof, I have signed my name to this specification, in the presence of two subscribing witnesses.

CARL WILHELM VOLLMANN.
